APPARATUS FOR CONTROLLING ELECTRICALLY TRANSMITTED MUSICAL PROGRAMS

Filed May 12, 1933

UNITED STATES PATENT OFFICE

2,065,037

APPARATUS FOR CONTROLLING ELECTRICALLY TRANSMITTED MUSICAL PROGRAMS

James L. Adams, Jr., Youngstown, Ohio

Application May 12, 1933, Serial No. 670,666

5 Claims. (CL 250—6)

The present invention relates broadly to the art of receiving program bearing audio and radio frequency impulses or signals transmitted over long distance telephone lines of the Pupin coil type, and through space as continuous electromagnetic waves, respectively.

More particularly, it pertains to specific means for greatly improving the clarity of resultant program as amplified by the usual receiver set, by preventing access thereto of many of the most annoying types of extraneous disturbing elements, now commonly brought in on substantially all broadcast programs, and known as the "background-noise" or the "noise-level" experienced by the mode of transmission involved.

One of the most important objects of my present invention is this material clarification of the incoming signal train of a vast majority of the commonly present "man-made" static noises now so common to radio-broadcast reception.

Another object of prime importance is to provide means for very effectively shielding the incoming signal train from lightning inductive effects, and similar atmospheric disturbances of the type so highly annoying to the listener.

A further valued object is to provide simple means for effectively putting the broadcast and/or wire transmitted programs on a "pay" basis, so that the customary "sponsoring" of such programs, with its attendant "advertising nuisance" elements, can eventually be eliminated, and thoroughly good programs substituted for the often mediocre and offensive variety now so predominant in the field, at least in so far as this country is concerned.

An additional object is to provide a switch-station, or control box, the interior of which can not be tampered with by the customer, access thereto being only available to the program-transmitting company, or the telephone company operating as its agent, as the case may be, by appropriate key.

An added object is to provide convenient means for bringing not only the transmission wires for the program service, but also the customary telephone twisted pairs, into the receiving customer's premises through a metal covered cable common to both, thereby consolidating the services, and aiding in elimination of extraneous noises.

An essential object is to provide convenient means whereby a customer can readily select from a diversity of excellent programs of the non-sponsored type, or if he so prefers at any time, he can throw-over to his own customary outside

aerial and receive the regular broadcast programs.

An incidental, but yet important object, is to obviate substantially all of the usual "spilling over" of the more powerful incoming programs into the programs being received on neighboring channels, as now commonly attendant to normal wireless reception. That is, my invention provides high selectivity on the non-sponsored type of audio-frequency programs transmitted. Yet another object is to provide programs free from the usual "fading" and the "mushiness", that is, the distorted and garbled speech and music incident to the periods of minimum received signal strength.

Other objects of importance will be obvious to anyone skilled in the art to which my invention appertains.

With all the above and other objects in mind, I have provided a simple type of apparatus for attaining concomitantly substantially all the objects enumerated, in a convenient and practical way.

In the drawing, Figure 1 shows a typical wiring diagram of my proposed invention;

Figure 2 is a similar wiring diagram showing the customer's station equipment more in detail;

Figure 3 shows a developed cross section of my adapter-plug, devised so as to show all the plugs and connections in one plane, for simplicity of exposition.

In all the figures, identical parts are designated by the same part numbers and letters, primes and sub-numbers being affixed in some cases, so as to distinguish between the two wires leading to the same tube filament, or the two wires which connect to opposite sides of a break made in a given line, as F₁ and F₂ of Figure 3.

The drawing is shown for purposes of illustration only, and not as determining the limits of my invention, or of its possible applications, and show a type of apparatus which may be readily applied to, or if desired even built in with, any customary type of standard radio-broadcast receiver, without great alteration thereto.

In accordance with the present invention, and referring now more particularly to Figure 1, there may be provided an apparatus including the control-box 11, preferably of fully-enclosed, metal, wall-mounting type, closed by the cover 12, substantially all the major portion of which has been broken away in order to show the interior construction of the box, but leaving enough to indicate the position of the riveted-on

hinges 13, and of the multi-tumbler "Yale" or equivalent lock 14, it being noted that the hinges will be of such type that the pins can not be withdrawn, (as by welding or brazing them into position,) and that the mounting screws 15 will be non-accessible except after opening the control-box by its proper key.

Furthermore, that even if the box were yanked off the mounting wall, then no assembling screws 10 of any sort will be found present upon the back face of said box, accessible for any tampering operations thereon, from the rear.

Entering the control-box at the top, via the grip-collar or split-bushing 16, is the lead-covered or equivalent metallic sheathed cable 17, indicated in dotted outline, and which is clamped solidly into place within the box, by the clamping-screw 18, also accessible only from the box interior.

20 Entering the control box 11 through this cable 17 are the plurality of audio-frequency transmission line taps 1 to 8 respectively, but which may include a greater or less number than here indicated, all shown single-wire for the sake of clarity, and appropriately connected in sequence to the similarly numbered points on the program-selector switch 19, here shown single-pole, for simplicity of illustration, but in reality usually of double-pole type, as indicated in the succeeding figure. The handle 20 of this switch is insulated from the latter, and made removable, so as to permit ready closure of the control-box lid, or such handle will be mounted directly in such lid, with a slip-key to ensure proper positioning whenever the lid is closed. The line numberings shown will be repeated upon the cover of box, and a pointer provided to take the switch-arm 19 position there, so that the position of the latter will be indicated upon the box exterior.

40 Also entering the control-box 11, there will usually be provided the radio-antenna down-lead 9, and if the customer is provided with a phone, there will be its incoming line 10, the former entering the box via the highly insulating bushing 21, and the latter via branch cable 17, in turn leaving the box via insulating bushing 22 and proceeding either under metallic cover or in the open, to the customer's telephone ringer and connection-box 23, and on to the phone 45 proper 24, with a line to ground at 25. As the lines entering top of control box 11, are shown single-wire, for simplicity, change-over to two-wire showing has been indicated by brackets, as at 26. Box 11, and cover 12, may, if desired, 50 each be provided with a drilled, projecting ear 21, through which customary twisted wire hairpin loop 28, and soft metal seal 29 may be attached, to further ensure against tampering.

60 Also emergent from the control-box 11, via another metal sheathed cable 30, with the split-bushing 31 clamped solidly thereon by the clamping-screw 32, likewise made accessible from the interior of control-box only, are certain wires F₁, F₂, A', and P₁, leading to the standard radio receiver set 33, shown at the left of this figure, and of which wires A' goes to the customary "antenna" binding-post on the radio-set's terminal board, while the other three go to the special adapter 34 shown in Figure 3, and positioned between the detector tube base 86 and its customary receptacle, by inserting the adapter 34 in place first in the receptacle, and then placing the tube base 86 in it. In this radio receiver 70 set 33, I have indicated the ground connection at 75

G_d, with a tap attached directly to the metal sheath of cable 30 by the clamp at 34.

In this elevation of the set, Sw. indicates the "on-and-off" switch; Vol. the volume control; Dial, the tuning dial; and L. S. the loud-speaker 5 position, as usual.

Reverting now to the control-box 11 again, I preferably place therein a double-pole, double-throw change-over switch 35, the two poles of which are insulated from each other by the cross-bar 36, but operated together by the insulated handle 37, which projects from the lower side of box 11, and may be thrown to the left to receive radio-frequency broadcast programs through space or to the right to receive voice or music bearing audio-frequency programs brought in from distant points through the transposed open wire lines, or preferably twisted-pair lead-cable transmission lines 38 to 43, inclusive, or the twisted-wire lines from local broadcast stations 44, 45, into the telephone exchange or equivalently functioning structure 46, and out through the lead covered multi-pair cable 47, from the entertainment or E section of which taps are taken from the wires 48, 49, 50, etc., at points 25 of entrance to customer's premises, as at 51, 52, 53, etc., 51', 52', 53' etc., 51'', 52'', 53'', etc., where the cable 17 previously mentioned, or the similar cables 17', and 17'' lead to the respective control-boxes 11, and the contained wires emerge 30 at the proper points on selector switch 19.

Customary telephone twisted pairs for regular telephone service enter the exchange 46 via lead covered cable 54 as lines 55, 56, 57, etc., and after passing through the usual selector switches 35 (not shown), emerge in the T section of cable 47, and are taken off in sequence to the successive telephone customer's premises via the taps 58, 59, 60, etc., and appropriate lines, one of which 10 has been described as going through the lead 40 cable 17, into and through the box 11 to the parts 23 and 24, of the usual customer's telephone equipment.

It has not been deemed necessary to designate all the tapped points shown in the T and E 45 sections of cable 47, as the further connections are self-evident.

One pole of selector-switch 19 connects at centre with the wire leading to the single-pole, single-throw disconnect switch 61, used by the 50 program distributing company to disconnect customer in case he is careless about paying for programs rendered. This switch is entirely non-accessible to customer. All wires are shown from here on.

55 The remaining terminal of this switch 61 may connect to and through the few-turn primary 62 of an audio-transformer 63, to point 64 on the upper side of right-hand throw of switch 35, then through point 65, and wire 66 to the remaining pole of selector 19, but which can not be shown here because of the one-wire diagram used on the latter. This will be shown in full, however, in connection with Figure 2.

The many-turn secondary 67, of transformer 65 63, may connect at its upper end to the positive side of a C-battery, the negative of which goes to grid 68, of an audio amplifier tube 69, whose plate 70 connects directly to the P₁ line through cable 30, at left side of control-box 11, while 70 lower end of secondary 67 proceeds to one end of filament 71, and also to the frame of box at 72. Opposite end of filament goes to point 73 on lower right side of switch 35, whose points 74 and 75 are connected together and also to F₁ 75

lead going to radio receiver set 33, and adapter 84. Point 76 connects to F_2 line in same cable. Antenna 9 connects to point 77, on upper left side of switch 35, and point 78 goes to antenna binding-post A' on the radio receiver.

On account of the impeding factor introduced by the passage of radio-frequency waves through the interior of a metal-sheathed cable, it may be better to shorten this length of cable 30 as much 10 as possible, as by mounting the control-box 11 directly on the side of, or underneath the radio receiver set 33, or if this is impossible, then to carry antenna 9 into, and lead A' from point 78 out of, the control-box via the same insulating 15 bushing 21, and across the air to point A' on radio connecting panel.

I believe that the signals through leads F_1 , F_2 , and P_1 will be not materially affected, provided 20 cable 30 can be made very short, since here the current flow proceeds both ways through the same opening in the metal sheath, and the impulses are not so much modified thereby, in consequence. 19 indicates an insulating coupling in shaft of handle 37.

25 An amplifying tube has been included in my control-box 11, as the preferred construction, but this inclusion may not always be necessary, if the delivered signals through lines 48, 49, 50, etc., of the E section of cable 47, are sent out 30 from exchange 46 after passing through adequate amplifying means there, (not shown).

In such case the transformer 63 will probably 35 be retained, however, so as to isolate the incoming lines from the customer's radio receiver equipment, the small C-battery shown connected with upper end of secondary 67 will be omitted and replaced by proper isolating condenser, and point 68 directly connected to the lead shown at 40 70, while the lower end of 67 will go directly to point 72, grounded on frame of box, and to nothing else, there being no filament present in this case within the box, but the F_1 and F_2 leads to switch 35 will remain as before, so as to cut out 45 the lighting of detector tube on radio receiver set, whenever signals are being brought in from the audio-frequency lines 51, 52, 53, et seq. to detector plate.

Referring now to Figure 2 I have again shown 50 the wiring diagram of the control-box 11 of my invention, but with the connections to selector-switch 19 shown in full, instead of "one-wire", as before, and with a typical set of connections for the radio receiver set 33 added at the left.

The radio receiver wiring-diagram Figure 2 55 covers simple, battery-operated, non-screen-grid tubes, but necessary changes to bring more nearly up to date and accommodate new screen-grid tubes, or those of the alternating-current heated filament type, will be self-evident to anyone skilled in the art.

I have shown two stages of tuned-radio-frequency (T. R. F.), a detector, and two iron-core 60 audio-frequency transformer stages, with output leads to loud-speaker (L. S.), A, B, and C batteries so labelled, a filament lighting switch (Sw.), filament rheostat (R), antenna (A') and ground (Gd) binding-posts on terminal panel, and the points of contact P_1 , F_1 , and F_2 , as made by the adapter 84 covered by Figure 3.

70 As the exact type of connections to be used within the radio receiver set proper 33 is non-essential to my invention, except in so far as the detector tube leads P and F_1 , and those to antenna A' and to ground Gd. are concerned, and as such 75 radio receiver connections in general are so

well known in the art, I have not considered it necessary to add an elaborate description thereof, but have felt that the showing made in Figure 2 would be sufficient, confining my further description to those points of contact with the leads F_1 , F_2 , and P_1 , emanating from my control-box 11, shown at the right of the figure.

An enclosing metallic shield 80 preferably surrounds the entire amplifying equipment, however, and is directly connected both with the 10 metal sheath of cable 30, and with the ground-lead Gd. of radio receiver set 33, as indicated. The T. R. F.-condensers will preferably be ganged.

The arrow-points on ends of leads P_1 , F_1 , and F_2 , at detector tube, show the positions at which 15 contacts are made by the adapter 84 of Figure 3, the break 81 in filament line F' , being produced by the adapter itself, as later described.

No further new elements appear in Figure 2, 20 that have not been already described.

In Figure 3, a developed cross-section of my adapter plug, which is to be inserted into the detector socket of the radio set, is shown, and which in turn is to then receive the detector tube of the said set, the base and prongs of which 25 tube are shown as inserted in the top of the adapter illustrated, with the filament, grid, and plate prongs identified by the customary initial lettering, F , F' , G , and P , respectively, while the adapter prongs just therebelow enter the similarly marked terminals in a receptacle or socket, (not shown), but preferably of the flat top type, and the adapter leads P_1 , F_1 , and F_2 , are carried over to the control box through the metal covered cable indicated in Figure 2. Note that P_1 30 is in effect a tap from prong P , whereas F_1 and F_2 are across the break 81 between the tube prong F' and the adapter prong 87 just below it, F_1 and F_2 being separated by insulating parts in the adapter, although this is difficult to bring out 40 clearly in the Figure 3 shown. The screw to which line P_1 is attached, however, simply connects directly with the spring 90, and the adapter prong 89, thereby forming a tap connection from the tube prong 91, against which the spring 90 45 bears.

Referring further to Figure 3, the break between lines F_1 and F_2 is indicated at 81, these lines connecting to the terminal screws 82 and 83, respectively, threaded into electrically separated 50 metal inserts imbedded in the base of adapter 84 of insulating material such as "Bakelite", the upper of which inserts mounts the spring 85 of copper or phosphor-bronze, which bears against the filament prong F' mounted in the radio-receiver detector-tube base 86, while the lower insert carries a metallic extension integral therewith, and in which the adapted F' -prong 87 is firmly mounted.

The end of lead P_1 is clamped under the screw 55 88, also threaded in an insert bushing which has a metallic extension in which the adapter P -prong 89 is mounted, and which likewise carries the conducting spring 90, adapted to bear firmly upon the tube P -prong 91, also mounted in base 86. The adapter G -prong mounted in a metal-bush insert and carrying a similar spring to contact with the G -prong of tube, is indicated at 92, while 93 shows the similarly devised adapter-to-tube-base F -prong connection and spring. The 60 G and F connections last mentioned have no screw and wire-lead connections attached thereto. A punched or drilled insulating plate for properly 65 positioning the entrance of prongs on tube-base 70 75

36, is firmly pressed into adapter 84, as indicated at 94.

The separate itemization of every minute detail-part in adapter has not been deemed necessary, so long as the exposition was clear, in view of space limitations.

It will be understood of course, that in the actual tube base and adapter used, the various prongs will be distributed in a pattern of usual type, and that for screen grid or alternating current heater tubes, still further prongs may be present, without affecting the items relevant to my invention, and the proper socket changes therefor will be self evident without further showing.

This completes the showing of parts of my invention, and of the apparatus to be used in more or less close association therewith. It will have been noted by anyone who has ever picked up broadcast programs by a radio receiver set, that where such programs are initiated say 3000 miles away and brought across country as audio frequency impulses by properly designed loaded telephone transmission lines, suitably transposed, and then broadcast through space at radio frequency by two stations, one of which is very close to the receiver, and the other off some very considerable distance, that in the presence of severe static conditions, the program emanating from the nearby local station will be substantially free from atmospheric static, whereas the same program coming in through space from the more distant station, may be almost ruined thereby. In other words, that the transmission at audio frequencies over the ultra long distance line has introduced very little, if any, static and other distortion effects, whereas even a very moderate distance through space may completely ruin an initially very fine program. This superiority of the long distance metallic lines is specially true for such distances as can be utilized in lead-covered cables, where the grounded sheath substantially wipes out from entrance thereinto, all exterior static elements.

45 I now propose to extend this sheathed protection right into the customer's premises, and at the same time utilize such sheathing as a means for prevention of access of many of the man-made varieties of "static", such as already enumerated, and likewise as a convenient means for elimination of unauthorized tampering with the wire plant supplied to each customer on his premises.

55 Since the continuous metallic enclosure of the lines prevents access thereto by other parties than those suitably supplied with the control equipment shown, it becomes possible to charge a modest sum per month for the program service rendered, so that direct revenue can be obtained therefrom without recourse to the nuisance of a "pay-box" or "coin-operated" device, and the highly objectionable sponsoring of programs eventually eliminated, with the normally attendant advertising excesses indulged in in the majority of such cases.

Thus not only "static" and similar intrusions, but the everlastingly obnoxious and pernicious advertising injections, may be in time wiped out, and a source of real revenue provided, to compensate for the supply of real music, in wide variety, and other worth-while forms of entertainment, over channels of assigned numbers, accessible to my selector-switch 19, on customer's premises.

Since the incoming programs would come in over twisted pairs, and the customer's telephone service ditto, within the same cable, clear up to the instruments, and not via long, non-twisted service lines through the open air, and often with considerable spacing between the respective leads, it is believed that a great percentage of the vacuum-cleaner, switching lamp, and telephone-dialing noises now picked up from nearby houses will be eliminated by the apparatus of my invention.

Since the programs would come in over twisted-pairs, the separate channels provided will be almost clear of cross-talk, or the spilling-over of any one program into an adjacent channel, as now is so characteristic an element of so-called radio reception.

But since there may occasionally be excellent programs coming in as at present through space, and which any given customer may elect to hear in preference to those which I have provided complete metallic circuits for, I have added the change-over switch 35 to permit such customer to quickly go over to normal radio frequency reception through space, by way of the antenna 9, and associated switch connections 17, 18, and the lead to A' on his radio receiver set.

This throw of the switch 35, by means of the handle 37, as shown in full lines in Figure 2, will short-circuit points 75 and 76, thereby close the break at 81, in filament line to F' side of detector tube, and thus light up this filament, provided main filament switch Sw. has been closed, and resistance R set properly.

It will be found that the plates of detector tube 33 and of the auxiliary amplifying tube 69, in control-box 11, are left in parallel, but that the throwing of switch 35 from the dotted right to the solid-line left-hand position, by handle 37, will have opened up the detector filament circuit and closed the amplifier tube filament connection from negative side of A-battery, through resistance R, to negative lighting-bus and up to just below break 81, out through line F' to point 74 on lower right side of the switch 35, out of point 73, through filament of tube 69 to point 71, thence to 72 and ground, and back from ground to positive lighting-bus of the radio receiver set, which connects through the lighting-switch Sw. to positive side of A-battery.

Thus the throwing over of change-over switch 35 similarly throws over the filament lighting from tube 69, in box 11, to the detector tube of radio receiver 33.

With one filament extinguished, the constant inter-connection of the plate elements of these two tubes will be of no material consequence, and is much simpler than trying to switch such plates back and forth also.

Throwing off either of the filaments will wipe out the transmission of any material signals through the respective tubes affected. Every listener to broadcast programs transmitted through space, to receivers non-equipped with automatic volume control devices, will have observed the periodic changes in strength of the incoming signals from distant stations, which is known as "fading", and is especially noticeable near the sun-down and sun-up periods. During the "minimum strength" periods, the signals from certain broadcasting stations are also very seriously "garbled" or altered by a so-called "mushiness", until the distorted music or voice 75

can not be recognized as such. This effect is not eliminated by automatic volume control, but is entirely absent, along with all the "fading" just mentioned, from the programs received at 5 audio-frequencies over the all-wire lines, suitably loaded and transposed, and which my invention utilizes.

It will be noted that I have provided means whereby my control-box and its associated wire 10 lines may be readily attached electrically to a standard radio-receiver without material alteration of its parts, and that when so attached, such control-box and its associated connected elements will provide means for the monthly collection of revenue for the wire-delivered programs, which revenues can not be so successfully collected from customers enjoying any of the space-borne radio programs broadcast from present radio-frequency stations, and that I avoid 15 use of all "pay-box" or "coin-operated" types of collecting means, which are such a great nuisance to the average customer.

In the use of the described apparatus of my 20 invention, certain very definite advantages thus accrue from the elimination of much of the deleterious "excess baggage" now brought in along with the customary space-borne broadcasts, together with the decided clarification of the general signal train, and the wiping out of most of 25 the obnoxious "static" influences.

Other important advantages accrue from the 30 substantial elimination of fading, and its often attendant pronounced "mushiness" or "garbling" of signals as added to the broadcast waves during 35 their passage through space.

Equally important advantages accrue from the provision of means whereby the transmitted wire 35 programs can be collected-for from the customer direct, eliminating the present necessity for "sponsored" programs and their many persistent advertising evils.

Added advantages accrue from the substantial 40 shielding-out of both atmospheric and man-made "static" influences, the roar of vacuum-cleaner motors, the click-click of phone dialing-signals, the usual outbursts of lightning, and 45 similar disadvantageous elements.

While I have shown and described a preferred 50 form of my invention, many modifications may be made, both in its structure and in the mode of operation, without departing from either the spirit of said invention, or the scope of my broader claims.

55 What I claim is:

1. In a method of receiving and electively selecting between broadcast radio-frequency program-bearing waves, and wire-transmitted audio-frequency program-bearing impulses, the 60 steps comprising the thermionic amplification of said impulses, and the amplification and subsequent rectification thermionically of the said waves, the paralleling of the outputs of said rectification and said first mentioned amplification 65 via a continuously maintained connection, the alternative energization of the electron-emitter heaters for said rectification and said first mentioned amplification only, and the translation of the resultant output from said rectification and said first mentioned amplification 70 in parallel, after further amplification of said resultant output by electro-thermionic means.

2. In a receiver of program bearing electric 75 impulses, a radio-frequency receiving unit contain-

ing a detector tube provided with a grid, a plate, and an electron-emitter, a socket for said tube, heating connections for said electron-emitter and connected with said socket, separate grid and plate connections for said tube also connected to said socket, an audio-frequency amplifier having an output circuit and connected to receive signals from the said plate connection, and a sound translating means coupled to the output circuit of said amplifier, a separate audio-frequency amplifier device containing an electronic amplifier tube provided with a grid, a plate, and an electron-emitter, separate connections therefor, a signal transmitting means interconnecting the two said plate connections permanently, a source of supply of heating current, throw-over switching means arranged for connecting said source to the heating connections of the said electron-emitters of the detector tube and of the said electronic amplifier tube alternatively, means for supplying the two said grid connections with radio-frequency and with audio-frequency program bearing impulses respectively, and a switch mechanism provided with an enclosing housing and a lock and key therefor, and connected to control the supply of the said audio-frequency impulses.

3. In a receiver of program bearing electric impulses, as in claim 83, an incoming cable with metal sheath, and containing program bearing 30 lines, and separate telephone lines, tapped connections from said program bearing lines leading into a customer's premises, a metal shield over the said tapped connections and connected with the said sheath over said cable, a metallic housing having assembly means and mounted over the said separate amplifier device, and also over the said switch mechanism, and a clamp for the said metal shield, said clamp being mounted within said housing and arranged so as to be 35 tightened only from the interior thereof, and by the aid of said key, said housing being built with all its said assembly means accessible from the inside only.

4. In a receiver of program bearing electric impulses, as in claim 83, an adapter having a plate connection, and electron-emitter heating connections, said adapter being mounted between the said detector tube and its said socket, and provided with a tap connection to the plate of 50 the said detector tube whereby the said signal transmitting means connects the plate last mentioned to the plate of the said electronic amplifier tube of the separate audio-frequency amplifier device, said adapter also having a contact connecting with the electron-emitter heating connections of said detector tube, and a separate contact leading to the electron-emitter heating connections of said electronic amplifier tube of the separate amplifier device through the said 55 switching means, whereby the latter can connect the said source of supply of heating current to the electron-emitter heating connections of said detector tube, and to those of said electronic amplifier tube of the said separate amplifier alternatively.

5. In an apparatus for receiving and electively choosing between space transmitted radio-frequency program bearing impulses, and wire transmitted audio-frequency impulses which are 70 also program bearing, a radio-frequency receiver containing an input circuit, a tuned radio-frequency amplifier stage connected thereto, a succeeding detector stage with a detector tube, and with plate, grid, and filament connections there- 75

for, a subsequent audio-frequency amplifier stage having an output circuit, and a sound translating means connected to the said output circuit, a separate audio-frequency amplifier stage having input leads and containing an amplifier tube, and having grid, plate, and filament connections therefor, an inter-connection between the plate of said detector tube and that of

said amplifier tube last mentioned, throw-over switching means arranged to heat alternatively the filaments of the said tubes just mentioned, an antenna connected to the said input circuit of the receiver, and means for supplying the said input leads of the separate amplifier stage with program bearing audio-frequency electric impulses.

JAMES L. ADAMS, JR.
